UNITED STATES PATENT OFFICE.

CLYDE P. ROSS, OF CHICAGO, ILLINOIS.

PROCESS OF AND APPARATUS FOR HANDLING AND MIXING COAL.

Application filed February 5, 1923. Serial No. 616,882.

To all whom it may concern:

Be it known that I, CLYDE P. ROSS, a citizen of the United States, residing at Chicago, in the county of Cook and State of Illinois, have invented a certain new and useful Improvement in Processes of and Apparatus for Handling and Mixing Coal, of which the following is a specification.

This invention relates to an apparatus and process for handling and mixing material, and particularly for handling and mixing coal. One object of the invention is to provide a homogeneous mixture of different grades of coal or other material which may be readily made, each grade of coal being added in a predetermined proportion. Other objects will appear from time to time throughout the specification and claims.

An apparatus for carrying out the process is illustrated in one form in the accompanying drawing, which is a partial vertical cross section of a coal handling plant.

Like parts are designated by like characters throughout.

A is a housing within which the coal mixing and handling apparatus is mounted. As here shown it is in the form of a concrete chamber. The parts might, however, be mounted separately on individual supporting frames and need not be enclosed. The housing A is provided with a sloping top A¹. It has a coal chute A² communicating with an inlet door A³. On the opposite side is a second coal chute A⁴ communicating with a second door A⁵.

I shall first describe the mechanism illustrated on the right hand side of the drawing. B is a gate mounted on the inside of the housing A and carried by a chain B¹. This chain is adapted to run over a sheave B² and is secured to a shaft B³. The shaft may be rotated by any suitable means the details of which are not here shown as they form no part of the present invention.

Mounted on the shaft B³ is a ratchet B⁴, and a pawl B⁵ adapted to engage the ratchet to prevent accidental reverse movement of the shaft B³. When the gate B is raised in the full line position coal will run into the feeder and will stand at about the line X. When the parts are in this position approximately 3750 pounds of coal will run into the feeder. If the gate be lowered to the position indicated in dotted lines, the coal will stand at about the line X¹. When in that position there will be 3250 pounds of

coal in the feeder. These quantities may of course be greatly varied by different proportioning of the parts and different setting of the gate B. I have given these merely to illustrate one form of combinations.

C is a feeder bin fixed on the inside of the housing A and in register with a door A³. It is irregularly shaped as shown and provided with an open top and with a hinged bottom gate C¹. The gate is provided with side aprons C² and stops C³. In the full line position shown it is closed and is held closed by a latch C⁴. This latch is opened by means, not here shown, to permit opening of the gate. Any other latch mechanism might be used as its details form no part of the present invention. Mounted on the bottom of the gate C¹ is a contact point C⁵ adapted to assist in closing the gate in a manner which will be described below. Mounted within the feeder C is a baffle plate D. It is fixed to the inner walls of the feeder and is also supported from the shaft D¹ which extends through the feeder.

Pivotedly mounted on the shaft D¹ is an under-cut gate E provided with side aprons E¹ E². The gate is provided in its top with a stop portion D². It is normally held closed in the full line position by means of a cable F which passes over the sheave F¹, and carries at its bottom end a counter-weight F². F³ is a second cable fastened to the member D² and passing over a sheave F⁴. By means of this second cable through any suitable mechanism, the gate may be pulled down so as to permit coal to run into the feeder C.

The mechanism shown on the left hand side of the drawing is generally similar to that just described. G is a gate, supported on a chain G¹, which passes over a sheave G² and is wound about a shaft G³ which carries a ratchet G⁴ and a pawl G⁵. The operation of these parts is the same as that of the corresponding parts above described.

H is a feeder bin provided with a door H¹ which has side aprons H² and a stop member H³. It is normally held closed by a latch H⁴ and has a contact point H⁵ by means of which it may be closed.

The feeder H is provided, as is the feeder C, with an under-cut gate I, provided with side aprons I¹ I² and a stop member I³. The gate is normally held closed in the position shown in full lines by means of a cable J which passes over a shaft J¹ and has at its bottom end a counter-weight J². J³ is a

second cable passing over the sheave J⁴. By means of this second cable the gate may be rotated from the position shown in full lines to the position shown in dotted lines 5 to open the inlet opening to permit coal to come into the feeder. The under-cut gate is mounted for rotation about the gate shaft K which passes through the center of the feeder H.

10 Mounted within the under-cut gate is a baffle L. It is swiveled within the gate at L¹. It is attached adjacent its other end to an adjusting screw M. This screw is engaged by a nut M¹ which is mounted for 15 rotation about the shaft K. On the outer end of the screw M is an operating handle M². By means of the handle the adjusting screw may be rotated and the baffle move in and out to vary the amount of coal which 20 may be taken into the gate and through it admitted to the feeder.

N is a track. O is a bucket provided with rollers O¹ adapted to run in the track N. The bucket may be of any suitable construction. 25 Its details form no part of the present invention. As here shown it is adapted to be raised and lowered by means of a cable O².

The bucket is provided in each side with 30 an extension P each of which extensions carries a roller P¹. When the bucket gates have been opened into the dotted line position and their contents discharged into the bucket O, it is raised and may be dumped 35 into a large bin or hopper or discharged in any suitable manner. As the bucket is raised one of the rollers P¹ P¹ contacts each of the points C⁵ and H⁵ on the gates and thus moves the gates to the closed position 40 where they are latched.

Although I have shown an operative device, still it will be obvious that many changes in size, shape and arrangement of parts might be made without departing materially from the spirit of my invention, and I wish therefore that my showing be taken 45 as in a sense diagrammatic. In particular the operation of the opening and closing of the bins and the raising and lowering of the 50 bucket may be considerably varied. The form of mechanism here shown is diagrammatic and I do not wish to be limited to the details of my present showing. Different arrangements might be provided within the 55 buckets for controlling the quantity of coal admitted to them and many changes may be made.

The use and operation of my invention are as follows:

60 Coal of different grades is introduced into each of the feeder bins. The vertically moving gate is adjusted at any suitable height. An undercut gate in each bin is then lowered and coal is allowed to run into 65 it until the bin is full. The undercut gate

is then preferably raised and the coal is discharged from the two feeder bins, the streams intermingling in the air and being received in a third bucket. That bucket is then raised at the will of the operator and 70 is dumped or discharged in any suitable manner.

I claim:

1. The process of completely mixing coal of different grades while freely falling, 75 which consists in downwardly discharging along separate but adjacent paths unmeasured quantities of different grades of coal, interrupting the downward movement of each of such streams of coal, discharging coal from each of said streams, in measured charges permitting said charges to fall freely through the air, into a common mixing zone in the air, and subsequently conveying the mixed material upwardly from 80 said mixing zone.

2. The process of completely mixing coal of different grades while freely falling, 90 which consists in downwardly discharging along separate but adjacent paths unmeasured quantities of different grades of coal, interrupting the downward movement of each of such streams of coal, discharging coal from each of said streams in measured charges along converging lines into a common mixing zone, and so timing said charges that they meet and mix while in motion in the air, and subsequently conveying the material so mixed upwardly from 95 said mixing zone.

100 3. The process of completely mixing coal of different grades while freely falling, which consists in downwardly discharging along separate but adjacent paths unmeasured quantities of different grades of coal, interrupting the downward movement of each of such streams of coal, and discharging coal from each of said streams, in measured charges permitting said charges to fall freely through the air, into a common mixing zone in the air.

105 4. The process of completely mixing coal of different grades while freely falling, which consists in downwardly discharging along separate but adjacent paths unmeasured quantities of different grades of coal, interrupting the downward movement of each of such streams of coal, discharging coal from each of said streams in measured charges along converging lines into a common mixing zone, and so timing said charges that they meet and mix while in motion, in the air.

110 5. In a coal mixing apparatus comprising 125 a plurality of adjacent hoppers, measuring receptacles positioned beneath and adapted to receive material from said hoppers, means for cutting off the flow of coal into said measuring receptacles, means for permitting the discharge of the contents of said meas- 130

uring receptacles, means for limiting the depth of the flow of coal into said measuring receptacles, and a common mixing receptacle adapted to be positioned beneath and between said measuring receptacles, and to receive the measured charges discharged therefrom.

6. In a coal mixing apparatus comprising a plurality of adjacent hoppers, measuring receptacles positioned beneath and adapted to receive material from said hoppers, means for cutting off the flow of coal into said measuring receptacles, means for permitting the discharge of the contents of said measuring receptacles, and a common mixing receptacle adapted to be positioned beneath and between said measuring receptacles, and to receive the measured charges discharged therefrom, and means for lifting

35

7. In a coal mixing apparatus comprising a plurality of adjacent hoppers, measuring receptacles positioned beneath and adapted to receive material from said hoppers, means for cutting off the flow of coal into said measuring receptacles, gates hinged along their bottoms normally closing the discharge openings of said measuring receptacles, means for opening said gates, a common mixing receptacle adapted to be positioned between and beneath said measuring receptacles, and to receive the measured charges discharged therefrom, means for lifting said mixing receptacle between and above said measuring receptacles, said mixing receptacle being adapted to contact said gates during its upward travel, and to close them.

Signed at Chicago, county of Cook and State of Illinois, this 2nd day of February, 1928.

CLYDE P. ROSS.
